COMBINED LAWN AND HEDGE TRIMMER

Harold Barnett Lamb, 1308 Lemon St., Tempe, Ariz.

Filed May 7, 1962, Ser. No. 70,002

Term of patent 7 years

(Cl. D40—1)

FIG. 1.

FIG. 2.

FIG. 5.

FIG. 3.

FIG. 4.

FIG. 6.

FIG. 1 is a front elevational view of the combined lawn and hedge trimmer, showing my new design;

FIG. 2 is a side elevational view;

FIG. 3 is a rear elevational view;

FIG. 4 is an elevational view taken from the opposite side of that shown in FIG. 2;

FIG. 5 is a top plan view; and

FIG. 6 is a bottom plan view.

I claim:

The ornamental design for a combined lawn and hedge trimmer, as shown.
